UNITED STATES PATENT OFFICE.

JAMES O. CRAWFORD, OF WACO, TEXAS.

SHADE AND DRAPERY FIXTURE.

1,211,094.

Specification of Letters Patent. Patented Jan. 2, 1917.

Application filed April 17, 1916. Serial No. 91,666.

To all whom it may concern:

Be it known that I, JAMES O. CRAWFORD, a citizen of the United States of America, residing at Waco, in the county of McLennan and State of Texas, have invented certain new and useful Improvements in Shade and Drapery Fixtures, of which the following is a specification.

This invention relates to certain new and useful improvements in shade and drapery fixtures.

The primary object of the invention is the provision of a fixture or bracket adapted for operatively supporting a window shade as well as a plurality of curtains or draperies adjacent thereto and readily attached to a window frame.

A further object of the invention is the provision of a window bracket that is inexpensive and easy to manufacture, which is ornamental in appearance and adjustable for the supporting reception of window shades and curtain poles.

In arranging the present device, it is contemplated to provide fixed plates at opposite sides of a window frame to which plates the curtain supporting slides are adjustably fixed while shade brackets are adjustably mounted upon the said plates, a unitary structure is formed for the mounting of the shade roller and two curtain poles or rods.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views: Figure 1 is a top plan view of one upper corner portion of a window frame provided with one of the present devices partially broken away and showing a shade roller and two curtain rods operatively mounted thereon. Fig. 2 is a vertical sectional view taken upon line II-II of Fig. 1, with the shade roller and the attaching screws removed. Fig. 3 is a perspective view of one of the window plates. Fig. 4 is a perspective view of one of the curtain supports detached. Fig. 5 is a perspective view of one of the shade brackets detached. Fig. 6 is a vertical sectional view taken upon line VI-VI of Fig. 1, and

Fig. 7 is an enlarged detail sectional view of the attaching end portions of one of the curtain supporting members.

It being understood that the device is provided for supporting a roller and rods forwardly of the upper portion of a window frame for suspending a shade and draperies in advance of the window, a portion of the top horizontal cross-piece of a window frame is herein illustrated at 10 in Fig. 1 of the drawings. A window plate 11 is secured upon the front side of the window frame adjacent the opposite ends of the piece 10 by means of screws 12 extending through perforations 13 of the said plates. The plates 11 are provided with inwardly-extending flanges or ways 14 adapted for the reception of side feet 15 of a curtain support 16 of channeled formation. Each curtain support 16 is provided with a shade bracket 17 having a foot 18 adapted to be slidably positioned beneath the outwardly bent central portion 19 thereof, the inward movement of the bracket foot 18 being limited by opposite lugs 20 carried by the foot 18 thereof. An arm 21 of the shade bracket 17 projects outwardly at right angles to its foot 18 and to the plate 11 and is provided with an upwardly opening slot 22 adapted to receive the metallic axle 23 of a shade roller 24 constructed in the usual manner, it being understood that the oppositely arranged shade bracket (not shown) will be provided with a perforation through the arm thereof for journaling the opposite cylindrical axle of the said roller 24. A winged set screw 25 is screw-threaded through an upstanding boss 26 upon the curtain support or slide 16 which is adapted to engage the upper face of the shade foot 18 for clamping the slide 16 and bracket foot 18 upon the window plate 11 and with the slide feet 15 engaging the flanges 14 of the window plate. Curved bars or goose-necks 27 and 28 of different lengths are shouldered into the curtain support slide 16, the bar 28 being of lesser dimensions than the bar 27 and positioned within the curvature thereof, it being understood that the said bars 27 and 28 are arranged in substantial parallelism with their supporting free ends 29 and 30 respectively, extending horizontally inwardly of the window and toward the oppositely-arranged curtain support. An extension nut 31 preferably having a roughened exterior surface although

- the same may be plain or otherwise ornamented if desired, is mounted upon a screw-threaded portion 32 of each of the bar ends 29 and 30 after the manner best illustrated 5 in Fig. 7 of the drawings. The threaded portions 32 of the bar ends are positioned inwardly of the free ends 33 of the said bars and the bars are reduced as at 34 outwardly of the screw-threaded portions 32.
- 10 The bore 35 of the extension nuts 31 is closely journaled upon the ends 29 inwardly of the threads 36 of the said nuts while the threads 36 being projectingly formed 15 inwardly of the nuts, are adapted to engage the annular shoulder 37 formed upon the bar ends 33 by overturning or heading such ends after the nuts are screw-threaded thereupon. It will thus be evident that the nuts 31 are prevented from being removed from 20 the bar ends 29 and 30 but are capable of a limited longitudinal movement thereof by reason of the aforementioned screw-threads.
- With one of the present devices arranged at the opposite sides of the window frame 10, 25 the shade brackets 17 and curtain supports 16 will be adjusted by means of the screws 25 the required distance apart for accommodating the shade roller 24 upon the two shade brackets 17 of the device. A curtain 30 supporting pole or rod 38 is provided for each of the goose-necks 29 and 30, each being of the same length substantially equal to the distance between the opposite faces 33 of the pairs of ends 30 and 29 which are arranged 35 in axial alinement with each other at the opposite sides of the window. Upon positioning one end of a rod 38 adjacent one of the bar ends 33, the extension nut upon such bar is turned upon the screw-threads 40 32 for moving the nut inwardly overlying the bar shoulder 37 and thereby receiving and retaining the rod end as best illustrated in Fig. 1 of the drawings. With two rods 38 so supported by the bars 27 and 28, a 45 curtain may be positioned over the inner rod carried by the bar ends 30 while an outer drapery may be mounted upon the rod 38 which is supported by the ends 29 of the outer bars 27, a shade being arranged upon 50 the roller 24 inwardly of the curtain when the device is in use. It will thus be seen that a readily adjustable combined shade roller bracket and curtain support is provided to which the curtain poles and shade roller may 55 be readily attached as well as removed therefrom when desired, while the device presents an ornamental appearance as well as possesses great utility.

While the form of the invention herein shown and described is what is believed to 60 be the preferred embodiment thereof, it is nevertheless to be understood that various forms, modifications and arrangements of the parts may be made without departing from the spirit and scope of the invention 65 as claimed.

What I claim as new is:—

1. A device of the class described, comprising a window plate having opposite inwardly projecting side flanges, a curtain support comprising a slide having opposite marginal feet shiftably arranged within the said flanges and having a channeled body-portion, an angular shade bracket having a foot 70 slidably arranged upon the said plate within the channel of said slide, limiting lugs carried by the said foot, a set screw upon the said slide adjustably engaging the said bracket foot when the device is operatively positioned, and goose necks of different 75 lengths outwardly projecting from the said slide, and adjustable curtain rod retaining extension nuts upon the free ends of the said goose necks.

2. In a curtain rod support, a bar having 80 a screw-threaded portion in spaced relations with the overturned free end thereof, the said bar being reduced between the said screw-threads and its end, and an extension nut having inwardly-extending centrally 85 arranged threads engaging the said bar threads and having one end thereof journaled upon the cylindrical portion of the bar inwardly of the screw-threaded portion.

3. A combined shade roller and curtain 90 pole bracket comprising a plate adapted to be fixed to a window frame and having opposite slide ways, a channeled slide shiftably mounted in the said ways, an angular shade bracket having a foot portion slidably 95 mounted upon the said plate within the channel of the said slide, a locking screw carried by said slide in engagement with the said bracket foot when the bracket and slide are in their adjusted positions, goose necks 100 outwardly-extending from the said slide in substantial parallelism and having their free ends extending inwardly of the window frame and provided with overturned shoulders at their free ends, and extension nuts 105 threaded upon the said goose-necks adjacent the said shoulders and having limited longitudinal movements thereon.

In testimony whereof I affix my signature.

JAMES O. CRAWFORD.
